CLAIM

The ornamental design for a reciprocating saw, as shown and described.

DESCRIPTION

FIG. 1 is a front perspective view of a reciprocating saw embodying my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged perspective view thereof, in which the area of enlargement is indicated by reference bubble 9 in FIG. 1.

The broken lines in the drawings illustrate portions of the reciprocating saw that form no part of the claimed design.
